UNITED STATES PATENT OFFICE.

JOHN R. GAMMETER, OF AKRON, OHIO, ASSIGNOR TO THE B. F. GOODRICH COMPANY, OF NEW YORK, N. Y., A CORPORATION OF NEW YORK.

PNEUMATIC SHOE-PRESS.

1,283,144.

Specification of Letters Patent. Patented Oct. 29, 1918.

Application filed September 7, 1917. Serial No. 190,251.

To all whom it may concern:

Be it known that I, JOHN R. GAMMETER, a citizen of the United States, residing at Akron, in the county of Summit and State 5 of Ohio, have invented certain new and useful Improvements in Pneumatic Shoe-Presses, of which the following is a specification.

This invention relates to an apparatus 10 for consolidating the elements of a rubber boot or shoe, prior to vulcanization, by means of compressed air or other suitable fluid under pressure. One of my objects is to provide improved means for supporting 15 the lasted shoe in operative position within the press chamber, and for packing the last or separating its vent outlet from the interior of said chamber. A further object is to enable the shoe press to be readily adjusted to accommodate shoes of different sizes. Preferably, also, I equip the press chamber 20 with a relief-valve controlled by the locking and unlocking movement of the cover, so that air pressure cannot be accumulated in 25 said chamber until the cover is locked.

Of the accompanying drawings,

Figure 1 is a vertical section of a pneumatic shoe press constructed according to my invention.

Fig. 2 is a section on the line 2—2 of Fig. 1, omitting the shoe and last.

Fig. 3 is a detail plan view showing the control valve in section.

Fig. 4 is a vertical section at right angles 35 to Fig. 1, omitting some of the lower parts.

Fig. 5 is a plan view of the apparatus partly broken away to expose the interior, with a shoe therein.

Fig. 6 is a sectional view showing a vented 40 last and a shoe thereon of a type adapted to be handled in the shoe press.

In the drawings, 10 is a pot or receptacle composed of a body casting 11, a cylinder 12 connected by bolts 13 to the lower end of 45 said body casting, the joint being packed by a soft ring 14, and a cover 15, said cover being swiveled at 16 on a bracket 17 hinged to the body casting at 18. The edge of the cover is packed by a soft ring 19 seated in 50 a groove in the body casting, and is interlocked with the body casting by locking means of the breech-block type, consisting of spaced projections 20, 21 on the cover and body casting respectively. 22 is a handle for

turning the cover on its swivel joint to lock and unlock it.

Compressed air is admitted to and discharged from the press chamber 23 in the receptacle 10, under control of a plug valve 24, to whose casing is connected a compressed-air supply pipe 25 and a pipe 26 leading to the chamber 23, there being a baffle plate 27 over the mouth of pipe 26 in said chamber to prevent the current of compressed air from impinging at full velocity 35 upon the lasted shoe. The casing of the plug valve has a discharge opening 28 leading to the atmosphere. The port 29 of the valve is shown in its admitting position in Fig. 3 and in its discharge position in Fig. 1.

30 is an upwardly-closing check-valve mounted on the cover 15 and controlling a passage 31 which leads from chamber 23 to the atmosphere, the stem 32 of said valve, when the cover is unlocked, coming under a plate 33 on the bracket 17 which is fixed at such a height that the valve 30 cannot close when under the plate, the object being to prevent the accumulation of pressure in chamber 23 if the workman should carelessly turn on the compressed air or leave it on when the cover 15 is not fully locked. When said cover is turned to bring the projections 20 under the projections 21, valve-stem 32 moves out from under the plate 33 85 and the valve will automatically close when the air is turned on. When chamber 23 is vented to the atmosphere, the valve 30 tends to drop by gravity, or, if it should stick, it may be positively opened by the action of a 90 cam surface 34, on plate 33, upon the end of the valve-stem as the cover is rotated to unlock it.

35 is a conoidal cup-shaped last-support 95 substantially elliptical in end or plan view as seen in Fig. 2, to correspond with the shape of the top or leg-end of the last, said support having a liner or packing member 36 composed of vulcanized soft rubber to effect the sealing of the interior of chamber 100 23 by means of the end of the last. The flaring or conoidal shape of this support and its liner, not only forms a proper sealing joint by reason of its shape, but also allows lasts of different sizes to be accommodated, Fig. 1 showing in full lines a small shoe and last, and in broken-lines a large one. The last-support is also adjustable up and down 105

for this purpose, and in order to keep a fluid-tight joint with the casing its periphery is formed as a piston 37 sliding in the cylinder 12 and provided with a packing 5 ring 38. To effect the adjustment, the stem 39 of the last-support is formed with a left-hand thread screwing in the end wall of a nut 40 which has a right-hand screw-threaded connection 40^a with the exterior of the cylinder wall, thus giving a quick motion when nut 40 is turned by means of a hand-wheel 41 formed thereon. An adjustable screw-stop 42 in the end wall of the nut 40 limits the relative retracting movement of 15 the parts and prevents the last-support 35 from being drawn entirely out of the cylinder 12. Broken lines in Fig. 1 represent the position of said support for a large last. At diametrically opposite points on 20 the last-support 35 are two upwardly-projecting guide-pins 43 working through lugs 44 on the body casting 11 to prevent the last support from turning.

45 is a spring plate fixed at its upper 25 end 46 and forming a heel or back rest for the lasted shoe, and 47 is an adjustable screw stop to fix the position of said back rest for different sized shoes. The plate 45 is slightly concave as indicated in Fig. 1 30 to conform to the back of the shoe. It will be noted that the axis of the cylinder 12 and the last support 35 is somewhat inclined from the vertical in an upward and rearward direction, so that the back of the 35 lasted shoe tends to rest by gravity upon the plate 45, while the top of the inverted last is supported and frictionally retained by the soft-rubber liner 36, an arrangement which allows the lasted shoe to be very 40 quickly inserted in and removed from its operative position in the press. 48 is a last which is preferably made hollow, of 45 cast metal such as aluminum alloy, and formed in the end or top wall thereof with air-discharge openings 49 connecting its interior with the atmosphere through a passage 50 formed in the stem of the last-support 35. Vent-holes 51 are also formed in the wall of the last at suitable points, and 50 particularly at the sole and ankle, to permit the escape of air from between the shoe and last into the interior of the latter and thence to the outer atmosphere as pressure is exerted upon the exterior of the shoe. 55 52, 52 are glazed openings in the cover 15 for viewing the interior of chamber 23 while under pressure.

An apparatus of this type is particularly adapted for operating upon arctics or other 60 rubber shoes with high flexible tops which are readily sealed against the surface of the last by the air pressure, Fig. 6 showing such a shoe with rubber (cloth lined) upper 53 and sole 54 and rubberized cloth top 55.

65 In operation, the cover 15 being unlocked

and swung back on its hinge 18 and the last support 35 and back rest 45 being adjusted to the proper positions for the particular size of shoe, a last 48 with a shoe thereon is placed in chamber 23 in inverted position, with the 70 top of the last resting in the conoidal cup-shaped packing member 35, and the back of the heel resting against the plate 45. Cover 15 is then closed and locked and the compressed air turned into chamber 23, its effect being to jam the last more tightly into the packing member 35 and also to press the shoe tightly against the surface of the last, the air between the shoe and the last being expelled through the vent holes 51 and the 80 elements of the shoe being consolidated by the difference between the pressure of the atmosphere on the inside of the last and the external pressure in chamber 23. The operation is very quickly performed and 85 when completed the chamber is opened, the lasted shoe removed and another one inserted. Vulcanizing is performed in the usual way and the result is a more perfect adhesion of the elements of the shoe and a 90 greater durability in service by reason of the pneumatic pressure employed.

I claim:

1. In a rubber-shoe press, the combination of a chamber for inclosing a lasted shoe, 95 a last having openings for the escape of air from between its surface and the lasted shoe thereon and a discharge opening in the top or leg-end wall of the last, means for supplying pressure fluid to the interior of said 100 chamber to press said shoe against the last, and an annular last-support including a soft packing member surrounding an opening to the atmosphere and forming an end-abutting surface for said top or leg-end wall of the 105 last to seal said chamber.

2. In a rubber-shoe press, the combination of a pressure chamber having compressed-air supplying and discharging means, and a support at the bottom of said chamber 110 for the top of an inverted vented last, said support including an annular conoidal last-packing member surrounding an air-vent opening.

3. In a rubber-shoe press, the combination of a press chamber having compressed-air supplying and discharging means, and a last-support at the bottom of said chamber having a substantially central opening to the atmosphere, and a conoidal soft-rubber liner 115 surrounding said opening and adapted to support and pack the end of an inverted vented last.

4. In a rubber-shoe press, the combination of a press chamber having compressed-air supplying and discharging means, and an annular last-supporting and packing member located at the bottom of said chamber and surrounding a vent-outlet opening, said member being adjustable in an up-and-down 120

130

- direction to accommodate lasts of different sizes.
5. In a rubber-shoe press, the combination of a compressed-air chamber and means for supporting a lasted shoe in an inverted, rearwardly and upwardly inclined position in said chamber, said means including an annular last top-end packing member surrounding a vent-opening to the atmosphere.
10. 6. In a rubber-shoe press, the combination of a compressed-air chamber and a piston in the bottom of said chamber adjustable in an up-and-down direction and having an annular last-packing and supporting member surrounding a vent-opening to the atmosphere.
15. 7. In a rubber-shoe press, the combination of a compressed-air chamber having a cylinder at its lower end, and a last-support having a conoidal annular last-packing liner surrounding a vent-opening to the atmosphere, said last-support being formed with a piston working in said cylinder.
20. 8. In a rubber-shoe press, the combination of a compressed-air chamber having a rearwardly and upwardly inclined cylinder at the bottom thereof, a piston adjustable axially in said cylinder, and a last-support carried by said piston and having an annular last-packing member surrounding a vent-opening to the atmosphere.
25. 9. In a rubber-shoe press, the combination of a compressed-air chamber having a cylinder at its lower end, a nut screwing on the exterior of said cylinder, a piston in said cylinder having a stem formed with an air-vent passage and provided with a screw-thread connection to said nut of opposite pitch to that of the nut and cylinder thread, means to prevent said piston from turning, and an annular last-supporting and packing member on said piston surrounding the vent passage.
30. 10. In a rubber-shoe press, the combination of a compressed-air chamber having a last-venting outlet in its bottom wall, an annular packing member surrounding said outlet and adapted to support the inverted
- last in an upwardly and rearwardly inclined position, and a heel back-rest for the lasted shoe.
11. In a rubber-shoe press, the combination of a compressed-air chamber having a last-venting opening in its bottom wall, means for supporting the inverted last in a rearwardly and upwardly inclined direction in said chamber, said means including a last-packing and supporting member surrounding said opening and adjustable in an up-and-down direction, and a transversely adjustable heel back-rest.
12. In a rubber-shoe press, the combination of a compressed air chamber, means for supporting and packing a vented last in an inverted upwardly and rearwardly inclined direction in said chamber, a spring plate forming a heel back-rest and fixed at its upper end, and an externally-accessible screw for varying the angle of said plate.
13. In a rubber-shoe press, the combination of a compressed-air chamber having a cover provided with locking and unlocking means, means for supplying compressed air to and discharging it from said chamber, means for supporting and packing a vented last in said chamber, and means controlled by the locking and unlocking of the cover for preventing the accumulation of air pressure in said chamber when the cover is unlocked.
14. In a rubber-shoe press, the combination of a compressed-air chamber having a cover rotatable in its own plane to lock and unlock the same, said cover having a relief opening to the atmosphere, an outwardly-closing automatic check-valve controlling said opening and having a valve stem, an abutment with which said valve stem is aligned by the unlocking movement of the cover to prevent the valve from closing, and means for supporting and packing a vented last in said chamber.

In testimony whereof I have hereunto set my hand this 6 day of September, 1917.

JOHN R. GAMMETER.
